United States Patent Office

Des. 215,256

Patented Sept. 16, 1969

215,256

COMB

Anton Rizner, Elmhurst, Ill., assignor to H. Fishlove & Co., Chicago, Ill., a corporation of Illinois

Filed Sept. 11, 1968, Ser. No. 13,484

Term of patent 14 years

Int. Cl. D28—03

U.S. Cl. D86—8

The side opposite that shown in FIGURE 1 is the same as that shown in FIGURE 1.

I claim:

The ornamental design for a comb, as shown and described.
